DESIGN FOR A COMBINATION WALLET, COSMETIC CONTAINER, AND CHANGE PURSE

Rita B. Bach, New York, N. Y.

Application May 31, 1943, Serial No. 110,331

Term of patent 14 years

To all whom it may concern:

Be it known that I, Rita B. Bach, a citizen of the United States and a resident of the city of New York, in the county of New York and State of New York, have invented a new, original, and ornamental Design for a Combination Wallet, Cosmetic Container, and Change Purse, of which the following is a specification, reference being had to the accompanying drawing forming a part thereof.

Fig. 1 is a front view in closed position of a combination wallet, cosmetic container and change purse showing my design.

Fig. 2 is a front view thereof showing the wallet in open position.

Fig. 3 is a perspective view thereof.

The rear of the wallet is substantially plain.

I claim:

The ornamental design for a combination wallet, cosmetic container, and change purse, substantially as shown and described.

RITA B. BACH.
